UNITED STATES PATENT OFFICE.

WILLIAM R. HOTCHKISS, OF ST. PAUL, MINNESOTA.

DESIGN FOR SAFETY PAPER.

Application filed September 11, 1925. Serial No. 14,750. Term of patent 14 years.

To all whom it may concern:

Be it known that I, WILLIAM R. HOTCHKISS, a citizen of the United States, residing in the city of St. Paul, county of Ramsey, said State of Minnesota, have invented a new, original, and ornamental Design for Safety Paper, of which the following is a specification, reference being had to the accompanying drawing, forming part thereof.

The drawing is a plan view on an enlarged scale of a sheet of safety paper showing my new design, the shaded and unshaded surfaces indicating contrast but not any particular color.

I claim:

The ornamental design for safety paper substantially as shown and described.

WILLIAM R. HOTCHKISS.
